UNITED STATES PATENT OFFICE.

FRANK H. STONER, OF MONROE, MICHIGAN, ASSIGNOR TO WILDER-STRONG IMPLEMENT COMPANY, OF MONROE, MICHIGAN, A CORPORATION OF MICHIGAN.

LAND-ROLLER.

1,345,515.

Specification of Letters Patent.

Patented July 6, 1920.

Application filed February 28, 1918. Serial No. 219,548.

To all whom it may concern:

Be it known that I, FRANK H. STONER, a citizen of the United States of America, residing at Monroe, in the county of Monroe 5 and State of Michigan, have invented certain new and useful Improvements in Land-Rollers, of which the following is a specification, reference being had therein to the accompanying drawings.

10 The invention relates to land-rollers and consists in the novel construction as hereinafter set forth.

In the drawings:

15 Figure 1 is a longitudinal section through the end portion of the roll;

Fig. 2 is an elevation thereof.

In the construction of land-rollers the cylinder and the heads therefor are frequently formed of sheet-metal, and the stub- 20 axles or trunnions by which the roll is attached to the draft-rigging are riveted or otherwise secured to said sheet-metal heads. With such a construction it is essential to have the heads formed of metal of sufficient 25 gage or thickness to form a firm connection with the trunnions, as otherwise they are likely to break out at the point of attachment. Such a heavy gage is not, however, required to carry the stresses from the trun- 30 nion into the cylindrical portion of the roll.

It is the object of the present invention to obtain a construction in which comparatively light gage metal may be used for the heads, and at the same time a strong attachment made between the same and the trunnions. As shown, A is the cylindrical body 35 formed of metal of suitable gage, and B are the heads formed of lighter gage metal and having the flanges C for attachment of the 40 same to the cylinder A. D are the trunnions, which are preferably formed of cast metal and are provided with enlarged hub portions E. To secure the hub to the sheet metal it is provided with an annular flange 45 portion F, which projects inward therefrom and extends through a corresponding perforation in the sheet-metal. G is an annular plate formed of metal of heavier gage than the head B and which fits around the 50 flange F to bear against the head. To secure the parts together the projecting portion of

the flange F, which is tapered, is peened over the member G, the metal being sufficiently malleable to permit of this operation. This will securely hold the parts together and will exert a clamping pressure upon the member G which will carry the stresses from the same and the hub E into the sheet-metal head.

With the construction as described the 60 head B may be safely formed of relatively light-gage metal without any danger of breaking away from the trunnion. This is due to the fact that the relatively large annular surface on the hub E which bears 65 against the head, together with the opposed surface of the member G, will so reinforce the light-gage metal as to safely carry all of the stresses to which it is subjected. The construction is also one which may be manufactured at small cost and in which the parts 70 may be easily assembled.

What I claim as my invention is:

1. In a land-roller, the combination with a cylindrical shell, of a head therefor 75 formed of relatively light-gage sheet-metal, a trunnion at the center of said head having an enlarged hub and an annular inwardly-extending flange passing through an aperture in said head, and a reinforcing ring on 80 the opposite side of said head engaging said flange, said flange being peened over said reinforcing ring.

2. In a land roller, the combination with a drum, of a head therefor, a trunnion having a hub portion of greater diameter forming an annular bearing against said head and a hollow portion extending through said head and peened over to clamp the 85 same against said hub portion.

3. In a land roller, the combination with a drum, of a head therefor, a trunnion having a hub portion of greater diameter forming an annular bearing against said head and a hollow portion extending through 90 said head, a reinforcing ring on the side of said head opposite said hub portion, and integral means on said hollow portion for engaging said reinforcing means and clamping 95 said head between said hub portion.

In testimony whereof I affix my signature.

FRANK H. STONER.
